UNITED STATES PATENT OFFICE.

EUGENE M. PLETCHER, OF PHILADELPHIA, PENNSYLVANIA.

INHALER.

1,231,787.

Specification of Letters Patent.

Patented July 3, 1917.

Application filed August 22, 1916, Serial No. 116,320. Renewed May 22, 1917. Serial No. 170,271.

To all whom it may concern:

Be it known that I, EUGENE M. PLETCHER, a citizen of the United States, residing at Philadelphia, in the county of Philadelphia and State of Pennsylvania, have invented 5 new and useful Improvements in Inhalers, of which the following is a specification.

This invention relates to inhalers, and has particular reference to an improved type of 10 inhaler capable of being carried in and supported by the nostrils.

The primary object of this invention is to provide a device of the above described character so constructed as to securely retain 15 the inhaler within the nostrils by means of resilient jaws formed therewith, thus eliminating the necessity of using the hand, straps or other devices for this purpose, the resilient jaws being engageable with the 20 cartilage of the nose in such a manner as to prevent the inhaler from becoming accidentally disengaged from the nose.

Another object resides in an inhaler which may be conveniently secured within the nostrils in a free and natural manner and will be sufficiently small to enable the user thereof to breathe naturally and without objectionable discomfort, even when resorting to violent exercise.

30 A further object is to provide an inhaler of the above character with novel means for supporting medicated material within the nostrils, said means being so constructed as to permit the user to receive the full value 35 of the medicine contained in the material.

Other objects of the invention will appear as the specification is read in connection with the accompanying drawings.

Figure 1 is a perspective view of the device, showing the same in applied position,

Fig. 2 is a side elevation of the device, showing the medicated material carrying members in section,

Fig. 3 is a perspective view, and

Fig. 4 is a bottom plan view.

Referring to the drawings in detail, the invention comprises a substantially U-shaped yoke 1, formed from any resilient material such as hard rubber, celluloid or the like, the 50 arms of the yoke being inclined inwardly as at 2, and enlarged at their free ends to contact with the septum of the nose a short distance above the lower end thereof. Pock-

ets 3 are formed by flanges upon the free ends of the yoke and are disposed in the same plane, having their confronting ends closed as at 4 while the outer ends are open to receive medicated material 5. The material 5 is preferably in the form of cotton, woolen, or felt wads which may be saturated with a suitable medicine, such as 60 menthol, oil of eucalyptus or the like. The plugs of absorbent material 5 are cylindrical in shape and of such length as to project beyond the open ends of the pocket, so as 65 to insure vaporization of the medicine with which said plugs are saturated. To further aid the vaporizing of the medicine within the material 5, the pockets are formed with longitudinally extending slots 6, which are 70 arranged at uniformly spaced intervals about the pocket, and open out through an end thereof. The slots 6 further serve to give a certain amount of resilient action to that portion of the pockets between the slots, 75 in retaining the material 5 in the pockets.

In operation, the material 5 is first placed in the pockets and then saturated with a suitable medicine whereupon the free ends of the yoke 1 are spread against the inherent 80 resiliency of the material of which the yoke is formed, whereupon the device is then placed within the nose in such a manner as to cause the confronting ends of the pockets 85 3 to engage the opposite sides of the cartilage of the nose, the medial portion of the yoke being disposed exteriorly of the nose to permit the ready removal of the device as is clearly shown in Fig. 1 of the drawings. It will thus be seen that the yoke 90 will cause the pockets to snugly engage the cartilage to prevent the accidental displacement of the device. The inhaler is now in active position, the medicated material being disposed directly within the nostrils to 95 permit the vaporizing of the same, as the person wearing the inhaler breathes. It will be manifest from the foregoing that I have provided a simple and efficient means for retaining the device within the nostrils of 100 the nose and to so engage the nose as to prevent bulging or distorting of the nostrils.

It is thought from the foregoing taken in connection with the accompanying drawings that the construction and operation of 105 this device will be apparent to those skilled

in the art and that minor changes in size, shape, proportion and that minor details of construction may be made without departing from the spirit and scope of the appended claims.

What is claimed as new and patentable is:—

1. An inhaler comprising a resilient U-shaped yoke, having enlarged ends, and annular flanges formed on the outer faces of

the enlarged ends, said flanges being slotted longitudinally.

2. An inhaler comprising a resilient U-shaped yoke having flanges on its free ends forming pockets with each pocket having 15 longitudinally extending slots opening out through an end thereof.

In testimony whereof I affix my signature.

EUGENE M. PLETCHER.
